METHODS OF AND MEANS FOR REDUCING NOISES AND VIBRATIONS PRODUCED BY SCREW PROPELLERS OF SHIPS

Ludwig Kort, Hannover, Germany

Application December 10, 1952, Serial No. 325,198

6 Claims. (Cl. 115—42)

This invention relates to methods of and means for reducing noises and vibrations produced by screw propellers of ships.

On screw-propelled ships the turning of the propeller or propellers almost always produces pronounced vibrations and noises, the sources of which vary somewhat on single and on twin screw ships and also depend upon the position of the propeller with respect to the ship's hull.

One of the objects of the present invention is to provide methods of, and means for, avoiding or at least reducing the vibrations and noises by reducing the sources of the impulses causing the vibrations or noises and by preventing the increase of the vibrations and noises by resonance.

The blades of a propeller turning near the stern of a ship meet on their circular path with water moving at different speeds caused by the wake distribution. Since the pitch of the propeller blades is uniform for at least each radius, they receive a shock each time a blade is passing through a zone of greater wake. One way to reduce such shocks somewhat is to reduce the pitch of the blade tips because in that case they act on a lever of about the total length of the blades. However, by this arrangement it is impossible to avoid reducing the propulsive efficiency. By the choice of an intermediate pitch of the blade tips corresponding to a mean acceleration of the water between the fast and the slow access speed of the water, the shocks and, therefore, the impulses producing the noises and also the said loss of propulsive thrust will be reduced to the practical minimum.

When the propeller is shrouded by a double-walled ring known in the art as a "Kort nozzle" and disclosed in Patents Nos. 2,030,375 and 2,566,525, the water is pre-accelerated between the mouth of the nozzle and the turning circle of the propeller and this of its own helps to minimize the shocks. On nozzle-enclosed propellers, it is also customary to reduce the pitch at the blade tips; however, in this case, chiefly because in their zone the speed of the water is reduced by its friction at the walls of the mouth part of the nozzle. In addition, there is a further possibility of equalizing the speed of the water arriving at the propeller disc by lengthening the nozzle body in front of the propeller within the zone of greatest wake. By this means, the fastest moving water, i. e. in the annular zone halfway between the tips of the propeller and the axis of the propeller, has time and additional distance to increase the speed of the slow moving water by friction before it reaches the propeller.

The present invention provides a method of reducing vibrations and noise produced by a screw propeller of a ship, consisting in considerably thickening the ship's structural materials adjacent to the noise-producing parts and (or) in fitting anti-vibration and noise-absorbing material onto the plating or filling the entire space between two opposed plates solid with the anti-vibration

2

and noise-absorbing material. The propeller blade tips are given a pitch which preferably corresponds to an intermediate acceleration of the water between the fastest and the slowest moving water at the blade tips.

5 In the case of a ship in which the propeller is shrouded by a nozzle, the method may consist in using heavy plating adjacent to the passing propeller blades and (or) fitting anti-vibration and noise-absorbing material to or between the plating of the radial sections of the nozzle body in the zone near to the propeller circle, or over the whole length of the radial sections.

10 Constructional forms of the invention are shown by way of example on the enclosed drawing, on which:

Fig. 1 shows the stern end of a twin screw ship in which, in the region of the propellers, the plating itself is either thickened or covered with a thick layer of noise-absorbing material;

15 Fig. 2 shows a Kort nozzle which, in the upper radial section, is partially filled with anti-vibration and noise-absorbing material, and which in the lower radial section is entirely filled with such material;

20 Fig. 3 also shows a Kort nozzle, the plating of which is covered on its inner surface with a layer of anti-vibration and noise-absorbing material; and

25 Fig. 4 is a side view of a Kort nozzle designed to meet the desired requirements referred to above. The length of the nozzle in front of the propeller disc is greater near to the underside of the stern of the ship than in the other portions because near to the ship there is the zone of greatest wake.

30 Referring to the drawings:

When the blade tips of a propeller (e. g. on a twin screw ship) pass the shell plating of the hull, altering pressure and suction forces are produced by which the plating tends to buckle and to move back as soon as the blade tips pass near to it and recede from it.

35 These movements of the plating are repeated each time the propeller blades come near to the hull and thereby produce strong vibrations and noises which are increased by the resonance of the adjoining shell plating.

40 When the distance between the blade tips and the hull plating is small or when the blades pass the propeller post or other appendages setting up no vibrations of their own, nevertheless there will always be a change 45 in the speed and the direction of the water leaving the blade tips. Furthermore, there may be formation of cavitation at these places, both producing a considerable noise which can be observed even at places far removed.

45 These disadvantages are reduced or are entirely avoided 50 either by thickening the shell plating, the propeller boss, the struts for the propeller bearings considerably or by fastening on the inside of the plating a layer *a* (Fig. 1) of material having qualities by which the vibrations are reduced, and such material may, for example, consist of concrete, light weight concrete, rubber, wood, marine-glue, artificial resin or similar products.

55 On propellers which are shrouded by a nozzle, the distance between the blade tips and the inside plating of the nozzle is uniform all around. Nevertheless, a 60 humming noise will be observed due to local vibrations of the nozzle plating when the blade tips are passing it. This noise can be greatly reduced by using heavy plates adjacent to the passing propeller tips or by filling the space between the inside and the outside of the nozzle body with the above mentioned anti-vibration and noise-absorbing material.

65 On the upper of the two radial sections through the nozzle, Fig. 2 shows a part-filling with such anti-vibration and noise-absorbing material while the opposite 70 radial section illustrates the manner in which the whole nozzle ring may be filled out with such material. In some cases, it may not be necessary to fill up the space

between the inside and the outside plates for it may be sufficient to cover or to line the inside of the plating with a layer of anti-vibration and noise-absorbing material as indicated by Fig. 3.

Having thus described my invention, I claim:

1. Apparatus for reducing the vibrations and noise produced by the rotation of a screw propeller of a vessel, comprising, a double walled nozzle ring surrounding the periphery of the propeller circle, and anti-vibration material filling the inner hollow space between the walls of the nozzle ring.

2. The apparatus of claim 1 wherein the anti-vibration material is concrete.

3. The apparatus of claim 1 wherein the anti-vibration material is limited to the area between the walls 15 adjacent the periphery of the propeller circle.

4. Apparatus for reducing the vibrations and noise produced by a screw propeller, including propeller blades, the pitch of which adjacent the tips corresponds to an intermediate acceleration of the water between the fastest and slowest moving water arriving at the blade tips, nozzle means for equalizing the speed of water arriving at the propeller disc and vibration damping means included in the nozzle adjacent the periphery of the propeller tips.

5. Apparatus for reducing the vibrations and noise 25 produced by the rotation of a screw propeller of a vessel comprising, a double walled Kort nozzle ring

surrounding the periphery of the propeller turning circle and a layer of noise-absorbing material fitted to the inside of the double walls of the nozzle body in the zone of the turning circle of the blade tips of the propeller.

5 6. Apparatus for reducing the vibrations and noise produced by the rotation of a screw propeller of a vessel comprising a double walled Kort nozzle ring surrounding the periphery of the propeller circle and a layer of noise-absorbing material fitted to the inside walls of the nozzle body covering the whole inside of the walls around the inner hollow space of the nozzle ring.
